attorney.

UNITED STATES PATENT OFFICE.

JACQUES CADGÈNE, OF ZURICH, SWITZERLAND.

METHOD OF PRINTING TEXTILE MATERIALS.

SPECIFICATION forming part of Letters Patent No. 780,636, dated January 24, 1905.

Application filed September 23, 1903. Serial No. 174,378.

To all whom it may concern:

Be it known that I, JACQUES CADGÈNE, a citizen of France, residing in Zurich, in the canton of Zurich, Republic of Switzerland, (whose 5 post-office address is No. 9 Seidengasse, Zurich,) have invented certain new and useful Improvements in Methods of Printing Textile Materials; and I do hereby declare the following to be a full, clear, and exact description of 10 the invention, such as will enable others skilled in the art to which it appertains to make and use the same.

I have applied for patent in France on April 6, 1903.

15 For some time past endeavors have been made to produce various designs on fabrics by the application of stencils and by the use of pulverized colors, but without any appreciable result. It may be said that this method 20 has never yet met with any industrial application. The patents taken out have remained in the theoretical stage owing to the innumerable difficulties found to be in the way of their practical application on an industrial 25 scale. At the present time by means of a well-known small apparatus, the "aerographe," designs are also reproduced by the spraying of colors and the application of stencils on the fabric; but this method still belongs rather to 30 the domain of art than to that of industry.

My invention consists in applying a greasy mastic on cloth by printing and forming a reserve and then in spraying colors on the cloth by the aid of steam or compressed air, thereby 35 obtaining any kind of pattern. Such patterns may be in the rainbow style, polychrome or monochrome. The cloth being unacted on by the colors in all places where it is covered by the printed mastic it follows that when this 40 mastic is caused to disappear by washing it with benzin the patterns remain well defined on such parts of the cloth as have not been covered with mastic.

In cloth-printing works the method of employing mastic as a pattern reserve is known; 45 but until now the cloth with the mastic reserve was dipped into a bath of dye, so that of course the cloth could only obtain a color of the monochrome style. With my process 50 by using pulverized colors in combination with a printed mastic I can by means of a num-

ber of pipes spray on the fabric as many colors as desired, which colors, according to my intention, are transformed into the rainbow style, polychrome or monochrome styles. 55 This is obtained by using vessels with the respective colors.

In the accompanying drawings, Figure 1 illustrates a portion of fabric having a design produced thereon in mastic. Fig. 2 is an elevation of a machine for use in carrying out 60 my method. Fig. 3 illustrates a portion of fabric wherein the parts *b* are covered by the mastic.

The method of carrying out this process is 65 as follows: First of all on the fabric *a*, Fig. 1, is printed, either by means of hand-blocks or by a mechanical printing-cylinder, an impression *b* in mastic of the desired pattern, the mastic being then dried at a moderate tem- 70 perature. When the mastic is dry, the goods are passed through a special machine, Fig. 2, wherein are disposed a certain number of pipes *c*, which act automatically and project the pulverized colors on the fabric *a* by means 75 of steam or compressed air. When the goods have received the desired colors, which takes only a few minutes, they are allowed to dry for four or five hours. At the end of this time the mastic is eliminated by washing the 80 goods in two successive baths of benzin. When the mastic has disappeared, the patterns *d* show up in a more decided manner, owing to the parts *b* reserved by the mastic remaining perfectly white. 85

What I claim is—

The process of producing on fabric designs of various styles as described without immersing the fabric in a color-bath, which consists in first applying to parts of such fabric a 90 mastic to produce a pattern, then spraying colors upon such fabric by steam or compressed-air jets, and subsequently removing the mastic.

In testimony that I claim the foregoing I 95 have hereunto set my hand this 26th day of August, 1903.

JACQUES CADGÈNE.
